(57) **CLAIM**

The ornamental design for the hook for pruner or blower, as shown and described.

DESCRIPTION

FIG. 1 is a perspective view of a hook for pruner or blower of the present invention;

FIG. 2 is a front view of the hook for pruner or blower;

FIG. 3 is a back view of the hook for pruner or blower;

FIG. 4 is a right side view of the hook for pruner or blower;

FIG. 5 is a left side view of the hook for pruner or blower;

FIG. 6 is a top view of the hook for pruner or blower; and,

FIG. 7 is a bottom view of the hook for pruner or blower.

The broken lines shown in the drawings illustrate portions of the hook for pruner or blower that form no part of the claimed design.
